Application November 4, 1944, Serial No. 561,858

10 Claims.

(Cl. 122—182)

This invention relates to hot water heaters for ships, homes, etc., and has for its object to provide a novel and improved heater of this type.

Another object of the invention is to provide a vertical downward-fired type of heater which is simple in construction, efficient in operation, and is considerably smaller and more compact than previous heaters of like capacity.

Another object is to provide a heater of the foregoing type including a novel and improved boiler which not only insures maximum transfer of heat but furthermore serves to insulate the combustion chamber as a protection against fire.

Still another object is to provide a heater of the type described which may be readily assembled and disassembled for inspection and cleaning, and which embodies various novel details of construction and features of operation whereby the flow of water and the movement of flue gases are so directed and related as to insure maximum transfer of heat and overall efficiency of operation.

Various other objects and advantages will be apparent as the nature of the invention is more fully disclosed.

Although the novel features which are characteristic of this invention are set forth more in detail in the claims appended hereto, the nature and scope of the invention may be better understood by referring to the following description, taken in connection with the accompanying drawings forming a part thereof, in which a specific embodiment has been set forth for purposes of illustration.

In the drawings:

Fig. 1 is a vertical section, taken on line 1—1 of Fig. 2, illustrating a heater embodying the invention;

Fig. 2 is a transverse section taken on line 2—2 of Fig. 1; and

Fig. 3 is a similar sectional view taken on line 3—3 of Fig. 1.

In the following description certain specific terms are used for convenience in referring to the various details of the invention. These terms, however, are to be interpreted as broadly as the state of the art will permit.

The heater shown in the drawings is intended primarily for supplying hot water to the heating systems of ships, small homes, etc. In the embodiment illustrated, it includes an outer casing 5 of rectangular cross-section having a removable cover 6 upon which is mounted an oil burner 7 of any suitable type including a downwardly projecting blower tube 8 containing vanes 9 for

imparting a swirling motion to the combustion gases which enter the combustion chamber, as hereinafter described.

The heater comprises a pair of concentric vertical cylinders 10 and 12, the former constituting the furnace tube and the latter constituting the outer wall of the unit. These cylinders are secured, as by welding, to an upper annular plate 13 spaced somewhat below the top of the unit, and to a lower annular plate 14 disposed adjacent the bottom of the cylinders, as shown in Fig. 1.

An annular band 16 welded to the inner wall of furnace tube 10 supports a refractory plug 17 and the superimposed annular blocks 18 of refractory brick which constitute the lining of the combustion chamber 20. The plug 17 is in the general shape of a Maltese cross with the sides 19 of the cross bars scrolled or sloping downward to impart a swirling motion to the downwardly directed stream of combustion gases.

A feature of the invention resides in providing the heater with a removable "wet bottom" unit comprising a cylindrical shell 21 which is of the same diameter as the outer cylindrical wall 12 of the heater and has spaced horizontal plates 22 and 23 welded thereto, as shown in Fig. 1. The cylinder 12 rests upon the shell 21, and a depending annular band 24 welded to the lower edge of cylinder 12 telescopes over the shell 21 and serves to center the two sections properly when they are brought together as shown in Fig. 1. The juncture of the two sections is preferably sealed with furnace cement. Suitable anchor clips 25 are welded to the bottom of shell 21 for the purpose of securing the heater to the floor.

The annular horizontal plates 13 and 14 between cylinders 10 and 12 serve to partition the heater into three separate chambers, as follows: an upper annular chamber 21 for the discharge of flue gases, the top of which chamber is formed by the cover 6; an annular boiler chamber 28 the side walls of which comprise the furnace tube 10 and the outer cylinder 12 of the heater; and a furnace chamber 29 which is open to the central combustion chamber 20 and has its bottom formed by the horizontal plane 22, as shown in Fig. 1.

The horizontal plates 22 and 23 in the lower section of the heater form the wet bottom chamber 30 of the boiler, which is connected by suitable pipe unions 31 to the lower end of the annular boiler chamber 28. Water is preferably circulated through the boiler by a suitable pump,

not shown, entering the wet bottom chamber 30 through pipe 32, then flowing through pipe unions 34 into the annular boiler chamber 28, and leaving the top of said chamber 28 through pipe 36. The wet bottom chamber 30 may be provided with a suitable drain pipe 33.

A multiplicity of small diameter fire tubes 35 extend vertically through the annular boiler chamber 28 and are secured to the annular plates 13 and 14 with their lower ends opening into the 10 furnace chamber 29 and their upper ends opening into the annular flue chamber 27. The chamber 27 is provided with a suitable pipe 36 for discharging the flue gases to the atmosphere.

A plurality of horizontal arcuate baffle plates 37 are mounted in staggered relation, and spaced apart vertically, in the annular boiler chamber 28, for the purpose of deflecting the rising column of water in chamber 28 in a tortuous course across the surfaces of the fire tubes 35. The 20 baffles 37 may be welded to the furnace tube 10 and cylinder 12 and are provided with holes through which the fire tubes 35 extend, as shown in Figs. 2 and 3.

In operation, the combustion gases from the 25 oil burner 7 are blown through the combustion chamber 20 at high velocity, a pressure blower preferably being employed for this purpose. The special design of the refractory plug 17 in the combustion chamber imparts to the hot gases a 30 swirling motion which results in higher heat transfer by virtue of the wiping action which the gases are made to take across the heating surface of the chamber. The air for combustion introduced by the blower on the oil burner 7 is given a swirling motion by the vanes 9 in the end of the blower tube 8 where it enters the combustion chamber 20. However, this swirling motion would be dissipated in the combustion chamber were it not for the specially designed plug 17 40 which amplifies and continues the swirling motion or rotary travel of the gases throughout the combustion chamber and lower furnace chamber 29 of the heater.

The hot gases swirling through combustion 45 chamber 20 impinge upon the upper plate 22 of the wet bottom chamber 30, which is in the area of hottest products of combustion, thus providing efficient transfer of heat to the water flowing through chamber 30. In addition to providing an efficient heating surface, the wet bottom chamber 30 also serves to insulate the boiler as a protection against fire. This is often extremely important, for example when the heater is employed in a wooden ship or is mounted on the wooden floor of a building, as in such case the fire box of an ordinary furnace would rest on or adjacent the floor and would constitute a serious fire hazard. This cannot happen with our heater because the bottom chamber 30 next to the floor, being filled with water, serves as a protection against fire.

As the water rises in the annular boiler chamber 28, the horizontal baffles 37 between the various fire tubes 35 serve to direct the flow of water across the tube surfaces, and, by creating a longer water travel and resultant high velocity through the boiler, serves to increase the transfer of heat from the flue gases in tubes 35 to the surrounding water. In practice, the space between cylinder 12 and the outer casing 5 is filled with any suitable type of insulation 38.

The provision of a multitude of small diameter fire tubes 35, coupled with a high ratio of heating surface to return flue area, results in high

5 velocity of gas travel through the heater. The high velocity of gas travel furthermore eliminates the necessity for a discharge stack, since the circulation of gases is not dependent upon draft created by a stack. These and the other novel features of construction heretofore described result in a higher output and higher efficiency with a smaller and much more compact heater design than has heretofore been possible.

Although a specific embodiment of the invention has been shown and described for purposes of illustration, it will be evident to those skilled in the art that the invention is capable of various modifications and adaptations within the scope and spirit of the appended claims.

The invention claimed is:

1. A hot water heater comprising spaced walls forming an inner combustion chamber and an outer boiler chamber, partitions closing the bottom of said boiler chamber and forming a flue chamber above said boiler chamber, a bottom section for said heater including a partition forming a furnace chamber open to said combustion chamber and a separate wet bottom chamber adapted to contain water to be heated, a plurality of fire tubes extending through said boiler chamber and opening into said furnace chamber and said flue chamber for conducting combustion gases to the latter, means for circulating water through said wet bottom chamber and said boiler chamber, and means for circulating hot combustion gases through said combustion chamber.

2. A hot water heater comprising spaced walls forming an inner combustion chamber and an outer boiler chamber, partitions closing the bottom of said boiler chamber and forming a flue chamber above said boiler chamber, a bottom section for said heater including a partition forming a furnace chamber open to said combustion chamber and a separate wet bottom chamber adapted to contain water to be heated, a plurality of fire tubes extending vertically through said boiler chamber and opening into said furnace chamber and said flue chamber for conducting combustion gases to the latter, means for discharging gases from said flue chamber, means for admitting water to said wet bottom chamber, means for circulating water from said wet bottom chamber upwardly through said boiler chamber, means for withdrawing the water from the top of said boiler chamber, and means for circulating hot combustion gases downwardly through said combustion chamber.

3. A hot water heater comprising spaced walls forming an inner cylindrical combustion chamber and an outer annular boiler chamber, partitions closing the bottom of said boiler chamber and forming an annular flue chamber above said boiler chamber, a bottom section for said heater including a partition forming a cylindrical furnace chamber open to said combustion chamber and a separate wet bottom chamber adapted to contain water to be heated, a plurality of fire tubes extending vertically through said annular boiler chamber and opening into said cylindrical furnace chamber and said flue chamber for conducting combustion gases to the latter, means for discharging gases from said flue chamber, means for admitting water to said wet bottom chamber, means for circulating water from said wet bottom chamber upwardly through said annular boiler chamber, means for withdrawing the water from the top of said annular boiler chamber, and means for blowing hot combustion gases downwardly through said combustion chamber.

4. A hot water heater comprising a pair of concentric vertical cylinders forming an inner cylindrical combustion chamber and an outer annular space, horizontal partitions closing the bottom of said annular space and dividing it into a separate upper annular flue chamber and a lower annular boiler chamber, a bottom section for said heater formed by a vertical cylindrical wall, a pair of horizontal plates dividing said bottom section into a cylindrical furnace chamber open to said combustion chamber and a separate wet bottom chamber adapted to contain water to be heated, a plurality of fire tubes extending vertically through said annular boiler chamber and opening into said cylindrical furnace chamber and said flue chamber for conducting combustion gases to the latter, means for discharging gases from said flue chamber, means for admitting water to said wet bottom chamber, means for circulating water from said wet bottom chamber upwardly through said annular boiler chamber, means for withdrawing the water from the top of said annular boiler chamber, and means for blowing hot combustion gases downwardly through said combustion chamber.

5. A hot water heater comprising a pair of concentric vertical cylinders forming an inner cylindrical combustion chamber and an outer annular space, horizontal partitions closing the bottom of said annular space and dividing it into an upper annular flue chamber and a lower annular boiler chamber, a removable bottom section for said heater formed by a vertical cylindrical wall, a pair of horizontal plates dividing said bottom section into a cylindrical furnace chamber open to said combustion chamber and a separate wet bottom chamber adapted to contain water to be heated, a plurality of fire tubes extending vertically through said annular boiler chamber and opening into said cylindrical furnace chamber and said flue chamber for conducting combustion gases to the latter, means for discharging gases from said flue chamber, means for admitting water to said wet bottom chamber, means for connecting said wet bottom chamber to the bottom of said annular boiler chamber for circulating water upwardly therethrough, means for withdrawing the water from the top of said annular boiler chamber, means

in said annular boiler chamber for directing the rising column of water therein across the surfaces of said fire tubes, and means for blowing hot combustion gases downwardly through said combustion chamber into the cylindrical furnace chamber in the bottom section of said heater.

6. A hot water heater according to claim 5, in which said water directing means comprises a plurality of baffles in the annular boiler chamber for deflecting the rising column of water across the surfaces of the fire tubes.

7. A hot water heater according to claim 5, in which said water directing means comprises a plurality of arcuate baffles mounted in staggered relation in the annular boiler chamber and spaced apart vertically to deflect the rising column of water across the surfaces of said fire tubes.

8. A hot water heater according to claim 1, having means in said combustion chamber for directing said gases in a swirling rotary path into the furnace chamber of said heater.

9. A hot water heater according to claim 5, having a refractory plug in said combustion chamber in the path of said combustion gases, said plug having a plurality of cross bars sloping downwardly to direct said gases in a swirling rotary path into the cylindrical furnace chamber in the bottom of said heater.

10. A hot water heater comprising spaced walls forming an inner combustion chamber and an outer boiler chamber, a partition forming a flue chamber closed off from one end of said boiler chamber, partitions at the other end of said boiler chamber forming a furnace chamber closed off from said boiler chamber and open to said combustion chamber and forming an end water chamber closed off from said furnace chamber, a plurality of fire tubes extending through said boiler chamber and opening into said furnace chamber and said flue chamber for conducting combustion gases to the latter, means for circulating water through said water chamber and said boiler chamber, and means for circulating hot combustion gases through said combustion chamber.
